UNITED STATES PATENT OFFICE.

WILLIAM H. COTHREN, OF FARMINGTON, MAINE.

GAS-REGULATOR.

SPECIFICATION forming part of Letters Patent No. 317,734, dated May 12, 1885

Application filed February 19, 1885. (No model.)

To all whom it may concern:

Be it known that I, WILLIAM H. COTHREN, a citizen of the United States, residing at Farmington, in the county of Franklin and State 5 of Maine, have invented certain new and useful Improvements in Gas-Regulators, of which the following is a specification, reference being had therein to the accompanying drawings.

10. Figure 1 is a vertical section taken longitudinally through my improved gas-regulator. Fig. 2 is a horizontal section through the regulator, taken in the plane indicated by dotted lines *x x* on Fig 2. Fig. 3 is a vertical transverse section through Fig. 2, taken in the plane indicated by dotted lines *y y*.

15. The object of my invention is to automatically regulate the flow and pressure of gas to burners, and at the same time provide for allowing the water or other fluids resulting from condensation in the regulator to escape by a siphon-drip, as will be fully understood from the following description, when taken in connection with the annexed drawings.

20. Before describing my invention I will state that I am aware of many automatic floating devices which have been arranged in chambers through which gas is allowed to pass, regulated by a valve connected to such devices, 25 mercury and other like fluids being employed as a fluid cut-off in connection with a valve.

It will be observed from what I will hereinafter explain that I employ a floating valve in combination with three chambers—to wit, 30 a fluid-pressure chamber, a valvular chamber, and a siphon-drip chamber.

The following is a description of my invention, which is fully illustrated in the annexed drawings, in which—

40. A designates the case or shell of my improved gas or fluid regulator. This case is rectangular in shape, and it is subdivided by two vertical partitions, *a' a²*, forming three compartments, *A' A² A³*. The compartment *A'* has a feed-inlet, *a*, on top, properly closed 45 by a cap or its equivalent, but preferably not air-tight.

At the lower end of the partition or vertical diaphragm *a'* is a space, *a³*, which establishes a fluid communication between the compartment *A'* and the compartment *A²*. The compartment *A²* is in communication with the

compartment *A³* by means of a siphon, *E*, the shortest limb of which communicates directly with the compartment *A²* below the water-level thereof. The longest limb of this siphon *E* terminates at its upper end in a contracted horizontal portion. It is desirable that the long and short legs of the siphon *E* should be so gaged and adjusted that all water of condensation, together with other fluids resulting from the condensation of the gas, shall be carried off through the siphon *E* from chamber *A²* as drip into the chamber *A³*, and from thence be conducted away from the regulator 60 through the apparatus.

B designates a pipe which communicates with the meter, and which has a seat, *b*, at its upper end, adapted to receive a valvular portion, *b'*, fixed to a cap, *b²*. This valve *b'* can 70 be made of any suitable material which will not be corroded by carburated hydrogen gas or any element mixed therewith. The cap *b²* is connected by posts *c* to an annular float, *C*, which is free to rise and descend in the 75 chamber *A²*, said parts being provided with diaphragm-guides *c'*, as clearly shown in the annexed drawings.

The float *C* may be made of metal, or it may be made of any other suitable material which 80 will serve as a buoy for the valve *b'* and its guides.

At the upper end of the chamber *A²*, and preferably directly above and coincident with the axis of the supply-pipe *B*, is the delivery-pipe *B'*, which communicates with the service-pipe.

E' is a suitable outlet, which may be closed by a cap applied at the upper end of the chamber *A³*, for the purpose of allowing the escape 90 of any undue accumulation of air.

The operation of my improved gas-regulator is as follows: I prefer to use as the fluid in my improved gas-regulator glycerine. This is supplied to the chambers *A' A²* through 95 the aperture *a* until a given desired level is obtained. When there is a gas-pressure from a head in the chamber *A²*, valve *b'* will be raised and the column in chamber *A'* will rise.

It will here be observed that I take advantage 100 of the superior weight of the column of fluid and the elasticity of the air above it. The effect of this will be that the column of fluid in chamber *A²* will, with the float *C*, descend,

and in proportion to the pressure of gas through the supply-pipe B so will be the position of the valve b' with respect to the seat b . It will thus be seen that by a very simple contrivance I am able to regulate the consumption of gas and have an even or uniform flow of the same, whatever may be the pressure. It will also be observed that the water of condensation and all foreign liquors will pass off through the siphon into the drip-compartment A^3 , and may be drawn off through the outlet E^2 .

While I have described glycerine as the preferable fluid to be used in my gas-regulator, I do not confine myself thereto, as any other suitable fluid may be used.

Having described my invention, what I claim as new is—

1. A fluid gas-regulator consisting of a case subdivided into three compartments A' A^2 A^3 , the supply-pipe, its floating valve, and the siphon-drip, substantially as described.
2. The combination, in a fluid gas-regulator, of a case, A, provided with a diaphragm terminating at a passage, a^3 , the compartment A^2 , having the supply and the delivery pipes and a floating valve therein, and a drip-chamber provided with a siphon and an outlet, substantially as described.
3. The combination, in an automatic gas-regulator, of the chambers A' A^2 and a siphon-drip chamber with the supply and delivery pipes, a float, and a valve guided by rods, substantially as described.
4. In a fluid gas regulator, a case subdi-

vided as described, a supply-pipe, B, an automatic float-valve, a delivery-pipe, B' , and a compartment provided with a siphon and outlets, substantially as described.

5. In a gas-regulator having a float-valve applied to the delivery-pipe, and two communicating fluid-chambers, an auxiliary chamber provided with a drip or draw-off inverted siphon, the longest limb of which has a horizontal portion, substantially as described. 45

6. In a gas-regulator, the combination with the partitioned case A, of a supply-pipe, a float, the horizontal guides therefor, the valve and valve-disk, a siphon in chamber A^3 , and a delivery-pipe, substantially as described. 50

7. A fluid gas-regulator consisting of a case, A, subdivided by partitions a' a^2 , forming three chambers, A' A^2 A^3 , a float having a flat guided valve, a supply and delivery pipe, a drip-chamber provided with an inverted siphon and openings E' E^2 , all constructed and adapted to operate substantially in the manner and for the purposes described. 55

8. In a fluid gas-regulator, a floating valve and a supply and delivery pipe located between chambers A' A^3 , in combination with a siphon and the outlets of the chamber A^3 , substantially as described. 60

In testimony whereof I affix my signature in presence of two witnesses.

WILLIAM H. COTHREN.
